Primary Examiner — Michael A Pratt

(74) Attorney, Agent, or Firm — Lora J. Graentzdoerffer

(57) **CLAIM**

The ornamental design for a fastening tool, as shown and described.

DESCRIPTION

FIG. 1 is a perspective view thereof;
 FIG. 2 is an alternative perspective view thereof;
 FIG. 3 is a left side elevational view thereof;
 FIG. 4 is a right side elevational view thereof;
 FIG. 5 is a top plan view thereof; and,
 FIG. 6 is a bottom plan view thereof.

The broken lines are for illustrative purposes only and form no part of the claimed design.
